James S. Key

UNITED STATES PATENT OFFICE.

THOMAS B. ATTERBURY, OF PITTSBURG, PENNSYLVANIA.

DESIGN FOR GLASS-WARE.

Specification forming part of Design No. 6,613, dated April 29, 1873; application filed April 11, 1873.

To all whom it may concern:

Be it known that I, THOMAS B. ATTERBURY, of Pittsburgh, in the county of Allegheny and State of Pennsylvania, have invented a new and useful Design for Glass-Ware; and I do hereby declare the following to be a full, clear, and exact description thereof, reference being had to the accompanying drawing making a part of this specification, in which—

Figure 1 represents a plan view of my design as applied to a section of a circular oval-faced glass dish, and Fig. 2 is a sectional view thereof in the line $x x$ of Fig. 1.

Like letters of reference indicate like parts in each.

My improved design consists of an oval-faced tapering rib extending radially out on the face of a glass article, with a radial prismatic edging between it and the edge of the dish, the same being repeated around the center of the dish or other article.

To enable others skilled in the art to make my improved design, I will proceed to describe the same.

The center, foot, stem, or knob of the dish

is represented at a on the face of the dish, and radially arranged outside the part a is a series of oval tapering ribs or corrugations, c . Outside of these, and between their larger ends and the lip or edge of the dish or other article, is a series of small prismatic ribs, s , which constitute an edging to the ribs a . The edge of the dish or other article is represented at b . The ribs a and edging s are repeated around the part a , and constitute my improved design; hence,

What I claim herein, and desire to secure by Letters Patent, is—

The oval tapering ribs a and prismatic edging s , arranged between the edge and center of the dish or other article, and repeated around such center, substantially as shown and described.

In testimony whereof I, the said THOMAS B. ATTERBURY, have hereunto set my hand.

THOS. B. ATTERBURY.

Witnesses:

W. N. PAXTON,
G. H. CHRISTY.
